DISPENSER

John S. Bonander, Camino, Calif.

Application April 19, 1941, Serial No. 389,347

3 Claims. (Cl. 221—98)

The present invention relates to means for dispensing granular material such as sugar, salt, or the like in which a measured amount of material is obtained upon tilting or inverting of the dispenser. The invention is concerned more particularly with the provision of an improved construction of this character which can be manufactured economically and which provides a simple, reliable machine for insuring accurate measuring of the desired amount.

It is a general object of the invention to provide an improved dispenser for dispensing measured amounts of granular material such as sugar upon tilting of the dispenser from an upright position to a tilted or inverted position.

Another object of the invention is to provide a dispenser of the character referred to having an improved trap chamber construction which insures accurate measurement of the desired amount of material.

Other objects and advantages of the invention will be apparent from the following description of a preferred embodiment thereof as illustrated in the accompanying drawing, in which:

Figure 1 is a vertical, sectional view through the dispenser taken in a plane at right angles to the trap chamber construction, as indicated by the line 1—1 in Figure 2.

Figure 2 is a vertical sectional view partly in elevation taken in a plane indicated by the line 2—2 in Figure 1.

Figure 3 is a plan view of the dispenser.

Figure 4 is a horizontal sectional view taken in planes indicated by the line 4—4 in Figure 2.

Figure 5 is a fragmentary sectional view taken as indicated by the line 5—5 in Figure 3.

Referring to the drawing, the dispenser includes an upright casing 10 which may be formed of Bakelite or other suitable material. The casing has a lid 11 hinged thereto as at 12. The casing 10 may be provided with a lip 13 at the intermediate portion of the hinge joint to insure a seal at this point. A suitable fastening device or clip 14 may be provided for the lid 11.

As previously pointed out, the dispenser is of the type which is tilted from an upright to an inverted position for dispensing operation. To form the dispensing conduit and trap chamber an insert or partition member 15 is removably seated in the casing 10 adjacent side wall 16 thereof. Side wall 16 is provided with a recess which with the wall 17 of insert member 15 forms a tapering discharge conduit 18 which leads to a discharge spout 18a. The insert member 15 is provided with side walls 21 which seat between retaining

projections or ears 22 on the adjacent side walls of the container 10. Adjacent its upper end each wall 21 of the insert member is provided with a round projection 23 which is seated in a similar depression in the side wall of the container. Side walls or flanges 21 are of sufficient resilience to yield upon insertion or removal of the partition member. At its upper portion, the wall 17 is provided with a handle 24 to allow removal and insertion of the insert member.

As previously stated, the insert member 15 and the casing 10 cooperate to provide a trap chamber of advantageous construction which chamber is indicated at 31. The chamber is located adjacent and extends across a lower corner portion of the casing between wall 16 of the casing and an upright partition 32 extending between side walls 21 of the insert member. The partition 32 is provided with an inclined upper face 33 providing a V-shaped feed opening with the adjacent portion of the wall 17 for the entrant portion of the trap chamber 31. The wall 32 is provided with an inclined surface 34 immediately below upper surface 33 and forming therewith a V-shaped projection from partition 32. Surface 34 is opposed to an inclined lip 36 formed at the lower edge of the wall 17 to form an entrance passage providing a reversing or zigzag path of flow leading to the trap chamber 31. The wall 36 and the wall 34 are preferably inclined slightly less than 45° with respect to the bottom wall of the casing.

About the trap chamber 31 the wall 16 is provided with a thickened portion 37 which facilitates feeding of material from the trap chamber to the discharge conduit 18.

In operation with the dispenser upright as shown in Figure 1, and with a supply of sugar in the container to a suitable level as indicated at 38, the sugar will flow between the wall 17 and the partition 32 in a reverse or zigzag path into the trap chamber 31 where it may assume a suitable level of repose as indicated at 39 for example. Upon tilting of the container in a clockwise direction from the position shown in Figure 1, the partition 32 prevents any flow of the material which is horizontally disposed with respect to the trap chamber 31 and as the casing is tilted to around 35 to 40°, for example, the lip 36 becomes horizontal and with the partition 32 begins to cut off the flow of material which was originally disposed vertically above the trap chamber. At the same time, the material within the trap chamber starts to flow out through the discharge conduit 18.

Further tilting of the dispenser completely shuts off the flow through the entrant portion of the trap chamber while the material within the dispenser rests against the upper wall 11 and the wall 17 of the insert member. Consequently, when the dispenser is again restored to upright position, any remaining sugar even though small in quantity will slide down the wall 17 and into the trap chamber. Thus the dispenser can be operated continuously until the supply of material is completely depleted.

I claim:

1. In a dispenser of the character operable by tilting from an upright position to dispense measured amounts of divided material, a casing having a recessed side wall with said recess tapering upwardly from the bottom wall of said casing, a partition member in said casing having a partition wall engaging said recessed wall to form a conduit, said partition wall terminating at its lower end in an inclined lip spaced from said bottom wall and diverging from said recessed side wall, and a second partition wall on said partition member extending upwardly from the bottom wall of said casing in spaced relation from said first partition wall, said second partition wall having a projection adjacent its upper edge above said lip and cooperating therewith to provide a zig-zag path of flow therewith.
2. In a dispenser of the character operable by tilting from an upright position to dispense measured amounts of divided material, a casing having a recessed wall, and a partition member removably seated in said casing to form a discharge conduit with said recessed wall, a trap chamber formed by a lower portion of said casing and said member, said chamber being in com-

munication with said conduit and with the interior of said casing, said member providing opposed walls having parallel portions similarly inclined with respect to the vertical and spaced apart to provide a zigzag entrance passage to said trap chamber which reverses the path of flow of material thereto, said passage having its entrant end facing upwardly and opening directly into the interior of said casing to provide for gravity feed of material thereto with said dispenser upright.

- 5 3. In a dispenser of the character operable by tilting from an upright position to dispense measured amounts of divided material, a casing having a recessed wall, and a partition member removably seated in said casing to form a discharge conduit with said recessed wall, a trap chamber formed by a lower portion of said casing and said member, said chamber being in communication with said conduit and with the interior of said casing, said member providing opposed walls having parallel portions similarly inclined with respect to the vertical and spaced apart to provide a zig-zag entrance passage to said trap chamber which reverses the path of flow of material thereto, said passage having its entrant end facing upwardly and opening directly into the interior of said casing to provide for gravity feed of material thereto with said dispenser upright, one of said opposed walls providing an upright baffle to prevent undesired horizontal flow of material upon tilting of said dispenser and the other of said walls providing a baffle to prevent undesired downward flow of material above said entrance passage upon tilting of said dispenser.
